FRAUD PREVENTING MECHANISM FOR
GAME APPARATUS

Joseph James Mitchell, Los Angeles, Calif.

Application November 14, 1932, Serial No. 642,517

5 Claims. (Cl. 273—118)

This invention relates generally to game apparatus of the character embodying a game board over which balls are adapted to be projected and to gravitate through openings in the board, certain of which openings may be associated with a pay-out mechanism in a manner to place the mechanism in an operative condition for the dispensing of checks or other considerations in accordance with different values of the openings.

In operating games of this character, unscrupulous players disturb the position of the apparatus from its intended playing position on a support, such as a counter, table or stand, by tilting or jarring the apparatus in an effort to maneuver a ball on the game board into an opening of the latter having a pay-out value, to thus cheat the game.

It is a purpose of this invention to provide a fraud preventing device particularly adapted, although not necessarily, for association with a game apparatus of the above described character, and which is automatically operable to prevent operation of a pay-out mechanism in the event that the playing surface of the apparatus has been jarred, tilted or otherwise disturbed in an effort to cheat the game.

It is a further purpose of this invention to provide a fraud preventing device which gives a visual indication of any attempt to cheat the game by manipulation of the playing surface from its normal playing position.

One form of the invention will now be described, following which the novel features thereof will be set forth in claims.

In the accompanying drawings:

Figure 1 is a side view partly in section, showing the invention in normal playing position;

Figure 2 is a side view partly in section, showing in full lines a pay-out slide partially advanced, and in broken lines the slide fully advanced to pay out its tokens.

Figure 3 is a side view partly in section, showing the fraud preventing device in action;

Figure 4 is a plan view of the invention in the normal playing position corresponding to that shown in Figure 1.

Figure 5 is a vertical transverse sectional view taken on the line 5—5 of Figure 1, and illustrating a different position of the mechanism.

Figure 6 is a fragmentary vertical sectional view taken on the line 6—6 of Figure 5.

Figure 7 is a fragmentary vertical sectional view taken on the line 7—7 of Figure 4.

Referring specifically to the drawings, this in-

vention in its present embodiment is adapted to be associated with a conventional "pin and marble" game apparatus of the type which includes a casing having an inclined playing surface on which balls are adapted to be projected by a suitable projecting device, the playing surface having openings at various locations through which balls are adapted to gravitate. Certain of such openings have predetermined pay-out values, and balls passing through these openings are adapted to be conducted in suitable runways to various parts of the mechanism of this invention for performing certain functions, as will be later described.

The mechanism embodying this invention is adapted to be installed in the casing of the game apparatus and comprises a base 9 on which are mounted a number of pay-out slides of the general construction and function shown in United States Letters Patent 1,697,537, issued January 1, 1929. These pay-out slides which in the present instance are three in number, are designated at 14, 15 and 16, and are adapted to be selectively actuated to deliver a greater or less number of checks or other considerations from a magazine 31 to a discharge chute 20, as will be understood by those versed in the art.

In the present instance three of the openings in the playing surface of the apparatus with which this mechanism is associated are intended to have various pay-out values, and balls passing through these three openings are adapted to be conducted respectively to three openings in a trap 10 to temporarily rest upon a stop bar 10^a spanning the upper open end of a rectangular container 10^b (Figures 4 and 5) on which the trap is hingedly mounted as shown in Figure 4. A ball passing into any one of the three openings in the trap 10 is confined in such opening when the trap occupies its lowered and active position shown in Figure 1, and is adapted to engage and depress a lever 10^c pivoted at 11 beyond one end of the container 10^b. It will be clear that the lever will be depressed different angular distances depending in which opening of the trap a ball is deposited, due to the different distances at which the trap openings are located with respect to the pivot 11 of the lever.

These varying amounts of angular movements of the lever 10^c are utilized to actuate a selector 19 which is pivotally mounted adjacent one end thereof on the inner section 10^d of a two section reciprocal plunger, the outer section 10^e of which is provided with a handle 12 by which manual operation of the plunger can be effected.

from exteriorly of the casing of the apparatus. In order to actuate the selector 19, a bar 18 projects downwardly from the lever 10^c and is adapted to engage and depress the selector 19 adjacent the pivoted end thereof so as to elevate the free end of the selector from its normal inactive position below the plane of the lowermost payout slide 16 as shown in Figure 3, to one of three active positions in which it is disposed to engage one or more of the slides 14, 15 and 16 in accordance with the extent to which the lever 10^c is depressed by a ball in one of the trap openings.

The outer section 10^e of the plunger is adapted to pass through the lower end of a vertical chute 11 when the plunger is moved from its retracted position of Figure 1 to its advanced position in Figure 2; and a ball passing through a certain other one of the openings in the playing surface of the game apparatus is adapted to be conducted by a suitable runway to the chute 11 so as to form an operative connection between the two sections of the plunger, so that when the operative connection is thus formed, and another ball occupies one of the openings of the trap 10 with the resultant movement of the selector 19 to one of its three active positions, actuation of the plunger will cause the selector to coact with one or more of the pay-out slides in advancing the latter to deliver one or more checks in accordance with the number of slides which are actuated.

A pivoted gate 32 operatively connected to the trap 10 by a link 33 (Figure 1) normally confines a ball in the chute 11 against discharge into a return chute 21, which may be of any suitable construction. During advancing movement of the inner section 10^d of the plunger, the gate 32 is engaged and raised by a lug 32^a on such plunger section, to swing the trap 10 upwardly to the position shown in Figure 2, so as to release from the trap any balls which have been deposited therein, these balls being then free to roll from the stop bar 10^a into the container 10^b, and to discharge from the latter into the return chute 21.

It is to be noted from a consideration of Figure 6 that upon the release of the outer section 10^e of the plunger, following operation of the pay out mechanism, a ball which has formed the operative connection between the plunger sections will be free to roll from the chute 10^e into the return chute 21 which latter is supported by an arm 21^a having hooked engagement with an arm 23 extending from the trap 10. A suitable operative connection (not shown) and forming no part of the present claimed invention may be provided between the arm 23 and the coin slide 29 to raise the gate 32 and release the inner plunger section 10^e upon the next operation of the coin slide in depositing a coin for the next game. It will be further noted that as the trap 10 is tilted during advancing movement of the plunger with a resulting lowering of the arm 23, that the return chute 21 is thus free to rock downwardly and discharge any balls which are deposited therein, so as to permit the balls to be conducted to a ball projecting device (not shown) by suitable runways.

In order to prevent cheating of the game as is possible by tilting or jarring the apparatus to maneuver a ball on the playing surface into any opening therein having a pay-out value, the following means is provided. A receptacle in the form of a cup 25 having its bottom wall de-

5 in a fixed position so as to be horizontally disposed when the game apparatus occupies its normal playing position on a support, such as a counter, table or stand, and to be visible from exteriorly of the casing of the apparatus.

In the present instance a weighted body 24 in the form of a sphere is disposed in the cup 25 and normally rests upon the upper concave end of a pin 26, which is urged upwardly through a central opening in the cup and has its lower end pivotally connected to a lever 27 pivoted intermediate its ends on the container 10^b and having an arm 28 with a hooked upper end adapted to engage the arm 23 projecting from the trap, as shown in Figure 4.

Should the position of the apparatus on its support be disturbed by jarring or tilting it so as to correspondingly move the playing surface of the apparatus, the body 24 will be displaced in the cup 25 so as to clear the pin 26 and permit the latter to move upwardly into the cup to the position shown in Figures 3 and 4, this movement of the pin being effected by rocking movement of the lever 27 and causing the arm 28 to coact with the arm 23 in swinging the trap upwardly and releasing from the latter any balls which have been deposited therein, thereby permitting the selector 19 to return to its inactive position so that actuation of the outer section 10^e of the plunger will be ineffective to operate the 30 pay-out slides even though a ball is forming the operative connection between the two sections of the plunger.

In order to restore the trap to its lowered and active position so that the pay-out mechanism 35 will be in an operative condition, it is necessary that a coin be inserted into the coin slide 29 and the latter actuated to cause its inner laterally projecting and hooked end 30 to engage and reversely rock the lever 27 by a camming action 40 as shown in broken lines in Figure 7, to restore the pin 26 to its normal lowered position so that the body 24 will no longer be obstructed by the pin and can gravitate to the center of the cup 25 and again rest upon the upper end of the 45 pin.

It will be appreciated that although the fraud preventing device in its present embodiment is shown and described in conjunction with a pay-out mechanism as a control against operation of the latter, that the device provides a visual indication of whether or not the playing surface has been disturbed from its normal playing position, and gives this indication until reset by the insertion of a coin, as the pin 26 maintains the 55 body 24 in an off center position with respect to the cup 25 until resetting of the device is effected by actuation of a coin slide or other means, if desired.

60 I claim:

1. Game apparatus having a playing surface adapted to be supported in a predetermined playing position; pay-out mechanism correlated with the game apparatus; a receptacle fixed relative to the playing surface; a spherical body in the receptacle free to roll from one position when the playing surface is tilted or jarred from its playing position; and control means for the pay-out mechanism including a movably mounted member maintained depressed by the body when occupying said one position so as to retain the control means inactive, and movable upwardly into the receptacle when the body rolls from said one position to render the control means active in preventing operation of the pay-out mechanism. 75

2. Game apparatus having a playing surface adapted to be supported in a predetermined playing position; pay-out mechanism correlated with the game apparatus; a receptacle fixed relative to the playing surface; a spherical body in the receptacle free to roll from one position when the playing surface is tilted or jarred from its playing position; control means for the pay-out mechanism including a movably mounted member maintained depressed by the body when occupying said one position so as to retain the control means inactive, and movable upwardly into the receptacle when the body rolls from said one position to render the control means active in preventing operation of the pay-out mechanism; and means correlated with the control means by which said member can be lowered to enable the body to return to its first mentioned position and to again maintain said member depressed.

3. Mechanism of the class described comprising a playing board having an opening to receive a ball, a control instrumentality engageable by the ball passing through the opening, a dispensing mechanism, manually controllable means operable to cause said ball to be effective through said instrumentality in actuating the dispensing mechanism, and a tilting control to prevent the ball from thus being effective when it has been

rolled into the opening by improper tilting of the board.

4. Mechanism of the class described comprising a playing board having an opening to receive a ball, a control instrumentality engageable by the ball passing through the opening, a dispensing mechanism, manually controllable means operable to cause said ball to be effective through said instrumentality in actuating the dispensing mechanism, and a tilting control to prevent the ball from thus being effective when it has been rolled into the opening by improper tilting of the board, said tilting control including a part normally held by gravity in an operative position, said part being movable to an operative position when the board is tilted, to prevent operation of said mechanism.

5. The combination with a game device having a substantially horizontal playing board of a tell-tale device for disclosing unauthorized tilting of the device, comprising a member formed with a well, a support extending upwardly from the bottom of said well and adapted to support a ball thereon, said ball adapted to be dislodged from said support upon tilting of the device, means operated upon dislodgment of the ball from said support to disclose the unauthorized tilting of the board.

JOSEPH JAMES MITCHELL.
